(No Model.)

G. R. & W. H. PERRY.

AIR CIRCULATING MECHANISM FOR RAILWAY CARS.

No. 467,195.

Patented Jan. 19, 1892.

Inventors
George R. Perry
William H. Perry
By their Attorney J. B. Thurston

UNITED STATES PATENT OFFICE.

GEORGE R. PERRY AND WILLIAM H. PERRY, OF CONCORD, NEW HAMPSHIRE.

AIR-CIRCULATING MECHANISM FOR RAILWAY-CARS.

SPECIFICATION forming part of Letters Patent No. 467,195, dated January 19, 1892.

Application filed October 1, 1891. Serial No. 407,467. (No model.)

To all whom it may concern:

Be it known that we, GEORGE R. PERRY and WILLIAM H. PERRY, citizens of the United States, residing at Concord, in the county of Merrimac and State of New Hampshire, have invented certain new and useful Improvements in Air-Circulating Mechanism for Railway-Cars; and we do hereby declare the following to be a full, clear, and exact description ⁵ of the invention, such as will enable others skilled in the art to which it appertains to make and use the same.

The object of this invention is to provide means for a thorough distribution of the air ¹⁵ entering the ventilators in the roof of a car.

The invention consists in a series of reciprocating fans hung upon the inner side of said roof; and it further consists in actuating mechanism located at either end of a ²⁰ car and driven by the action of the outer air while a train is in motion.

Similar reference-letters designate like parts throughout the various views of the drawings.

²⁵ The invention will be fully set forth in the following specification and claims, and clearly illustrated in the accompanying drawings, forming a part thereof, in which—

Figure 1 represents in dotted lines a car, ³⁰ showing the roof and our improvements applied thereto in longitudinal section. Fig. 2 is an enlarged end elevation of a car, showing our improved air-receiving funnels, one at each end. Fig. 3 shows a cross-section of ³⁵ the roof of a car provided with our improved air-circulating device and the lines of the car-body carried down in dotted projection. Fig. 4 is an enlarged broken view showing a detached portion of our air-circulating mechanism. Fig. 5 is an elevation of the driving ⁴⁰ mechanism, showing a portion of its inclosure in broken section.

A is the body of a car; B, the roof; C, the compartments at either end, in which is located ⁴⁵ an air-receiving box D, containing an air-actuated motor-wheel E, the axle e of which is mounted in said box D, one end extending through the same and carrying a

crank F. A driving-bar G connects said crank with a connecting-rod H, which connects with and transmits motion to the several reciprocal fans I, carried in the supports J, secured to the car-roof. Funnels K are arranged, one at each end of a car, passing through the roof and entering the air-box D ⁵⁰ at a proper location to conduct the air directly upon the motor-wheel E, after which said air is discharged through the outlet L. The throat of the funnels K may be provided with a valve k, by which the speed of the motor-wheels E may be regulated or entirely stopped, the valve at the rear of a car being always closed and the driving-bar G detached from the rod H while the opposite motor-wheel E is driving the reciprocal fans I in the car. ⁵⁵ This valve k may consist in a simple slide, as shown in the enlarged view, Fig. 4, provided with a pull-cord k', having a ring k² attached to its lower end, and at the opposite end of said valve one or more helical springs k³ may ⁶⁰ be attached in a manner to hold said slide normally closed.

Having described our invention, what we claim is—

1. In a car-roof, a series of reciprocating ⁷⁵ fans, a rod running lengthwise of said roof and pivotally connected to each of said fans, air-compartments C, located one at each end of said roof, having an air-inlet orifice provided with a funnel K and a discharge-orifice ⁸⁰ provided with a pipe L, air-actuated motor-wheels mounted, one in each compartment, upon a suitable driving-shaft passing through one side of said compartment, a crank mounted upon the projecting end of said shaft, ⁸⁵ and a driving-bar connecting said cranks with the ends of the rod H, all substantially for the purpose set forth.

2. An air-circulating apparatus for cars, comprising a series of reciprocating fans ⁹⁰ mounted in the car-roof, a rod running lengthwise of said roof and pivotally connected to each of said fans, a driving-bar connecting either end of said rod with the crank of a shaft e, mounted in a compartment C at each ⁹⁵ end of the car-roof, having suitable air inlet

and discharge orifices, and an air-actuated motor-wheel mounted upon each of said shafts *e* within the said compartment C, and a suitable valve for controlling the air and graduallyating the speed of said motors, all combined and arranged substantially for the purpose set forth.

In testimony whereof we affix our signatures in presence of two witnesses.

GEORGE R. PERRY.
WILLIAM H. PERRY.
